UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

RADIANT AIR HEATER.

Application filed April 21, 1924. Serial No. 707,873.

My invention relates to electric heating devices and particularly to electric radiant air heaters.

One object of my invention is to provide a radiant heater of the reflector type having a relatively simple and easily manufactured supporting and carrying means.

Another object of my invention is to provide a radiant reflector-type heater having a single means for pivotally supporting the reflector on a base, for clamping a heating unit in its proper operative position therein and for providing a carrying means for the heater.

In practicing my invention, I provide a concave reflector with a wire guard and mount therein a radiant heating unit. An extended member of arcuate form, is secured to the rear surface of the reflector and has its upper end formed to constitute a carrying handle and its lower end formed to constitute a pivotal mounting means on a suitable base.

In a modified form of construction, a single extended arcuate member is secured to the rear surface of the reflector and has its lower end pivotally mounted on a base, while an intermediate pressed-out portion is effective to clamp a heating unit in its proper operative position in an axial opening in the reflector, while the upper end thereof is formed to constitute a carrying means for the heater.

In the drawings,

Figure 1 is a view, in side elevation, of a radiant heater embodying my invention,

Fig. 2 is a view in rear elevation thereof,

Fig. 3 is a view, in side elevation, of a modified form of radiant heater embodying my invention,

Fig. 4 is a view, in rear elevation thereof,

Fig. 5 is an enlarged fragmentary view, in vertical section, of a portion of a radiant heater embodying my invention, and

Fig. 6 is an enlarged view, partially in rear elevation and partially in lateral section, of the central portion of a device embodying my invention.

Referring more particularly to Figs. 1 and 2 of the drawings, a radiant reflector-type heater 11 comprises a reflector member 12, of concave or bowl-shape that has a removable wire guard 13 mounted at the front thereof. A plurality of substantially radially-extending wire members 14 constitute a

part of the guard 13, the inner ends of which are suitably secured against an annular ring 15. A plurality of the wire members have their inner ends extended beyond the annular member 15, as indicated by the numerals 16 and 17 in order that they may constitute a means for holding the wire guard against the reflector 12.

A radiant and elongated heating unit 18 is mounted within the concave surface of the reflector member 12 and is aligned axially thereof, extending through an axial opening (not shown). In general, the heating unit 18 comprises a suitable refractory support 19 and a resistor member 21 wound thereon.

The heating unit 18 is removable from the refractory support in a rearwardly direction. An annular and rearwardly extending tubular holder 22 is suitably secured to the reflector 12 and a screw-cap clamping member 23 has screw-threaded engagement with the member 22, whereby an integral and enlarged intermediate portion of the heating unit 18 is clamped therebetween and the heating unit is held in substantially its proper operative position relatively to the reflector.

A rearwardly-extending metal shell 24 comprises a part of the heating unit 18 and is effective to protect a pair of spaced contact terminals 25 and 26 that are mounted at the rear end of the assembled unitary heating structure 18. As the construction of the heating unit and of the mounting means therefor constitutes no part of my invention, it is not illustrated or described in detail. It is, however, more particularly disclosed and claimed in Patent No. 1,425,638, issued August 15, 1922, to F. F. Forshee and assigned to the Westinghouse Electric Products Company.

A combined heater carrying a pivotal-supporting means comprises a member 27 that is of extended arcuate form, having its upper end shaped to constitute a handle or carrying member 28 and having its lower end formed to constitute a pivotal mounting portion 29 that is in operative engagement with a suitable base 31. The member 27 is secured against the outer rear surface of the reflector 12 by a plurality of rivets 32, 33, 34 and 35, the member 27 having an elongated opening 36 therein in order that the member 22 and the rear portion of the heating unit 110

18 may extend therethrough. An opening 37 is provided at the upper portion thereof in order to permit of an operator inserting his fingers to carry the heater, the handle portion 28 being bent outwardly and rearwardly as is more particularly shown in Fig. 1 of the drawings.

19 Stiffening ribs 38 and 39 are provided at the upper handle portion to permit of making the member 27 out of relatively thin sheet metal, while still obtaining sufficient 70 rigidity.

20 Integral and laterally-extending flange portions 41 and 42 constitute a part of the lower end portion 29 to provide sufficient 75 rigidity and also to provide members through which a pivotal mounting means, comprising a machine bolt 43, may extend, the bolt passing also through an integral top portion of the base 31.

21 A nut 44 holds the bolt 43 in its proper operative position and permits of obtaining sufficient frictional engagement between the co-operating parts to hold the reflector 25 and heating unit in any desired angular position relatively to the base.

26 Referring more particularly to the modification illustrated in Figs. 3 to 6, inclusive, of the drawings, a radiant reflector heater 45 comprises a reflector member 12 of concave or bowl shape that has mounted at the front thereof a removable wire guard 13, the guard 13 comprising a plurality of substantially radially extending wire members 14, the inner ends of which are suitably secured against the annular ring 15. A plurality of wire members have their inner ends extended beyond the annular member 15, as indicated by the numerals 16 and 17 in 40 order that they may constitute a means for holding the wire guard against the reflector 12.

27 A radiant and elongated heating unit 18 is mounted within the concave surface of the reflector 12 and is alined axially thereof, extending through an axial opening 46 that is illustrated more particularly in Fig. 5 of the drawings.

28 The heating unit 18 there illustrated, comprises a suitable elongated refractory support 19 that has an enlarged rear end portion 47 providing an annular shoulder portion 48. A resistor member 21 of any suitable type and construction is wound upon the forwardly extending cylindrical portion of the heating unit 18.

29 A rearwardly extending flange portion 49 is provided at the rear surface of the reflector 12 immediately surrounding the opening 46 against which the shoulder portion 48 of the refractory member 19 may rest.

30 It is obvious that the heating unit 18 is removable from the reflector member in a rearwardly direction. A member 51, of 65 elongated arcuate form, comprises a pressed

31 metal member that is provided with a pair of side flanges 52 and 53 that extend along substantially the entire length of the member 51. At the lower end the flanges 52 and 53, operatively engage the reduced top portion of a base member 31 and are provided with openings therethrough, through which a pivotal mounting means constituted by a suitable machine bolt 43 may extend. A wing nut 44 is mounted on the outer end of the machine bolt 43 to suitably clamp the flange portions 52 and 53 against the sides of the member 31, in order that the member 51 may be held in any desired position angularly relatively to the supporting base 31.

32 The member 51 is secured against the rear surface of the reflector member 12 by a plurality of suitable machine screws 54, any desired number of which may be employed and which respectively extend through the reflector and the intermediate portion of the member 51 and are held by co-operating nuts 55.

33 The upper part of the member 51 is constituted by extensions of the flanged portions 52 and 53 that are respectively provided with openings 56 and 56^a therethrough, that may be engaged by the thumb and finger of an operator to permit of carrying the entire heater.

34 While I have illustrated a different shape of upper end of the member 51 from that illustrated in Figs. 1 and 2, of the drawings, either of these modifications may be employed, as may be suitable or desired.

35 The intermediate portion of the member 51 is provided with a rearwardly extending integral portion 57 that comprises two parts. One part 58 is of such internal diameter and length as to receive the rear end portion 47 of the refractory member 19 and to clamp it securely against the annular flange member 49 by a shoulder portion 59. The shoulder portion 59 connects the part 58 with a second part 61 that may be of relatively small diameter, and of such axial length as to provide sufficient space for the inner ends of twin conductors 62 and 63 of a suitable supply circuit cord 64 that extends into the member 61 through a bushing 65 of insulating material that is located in an axial opening 66 in the part 61.

36 The inner ends of the conductors 62 and 63 are secured to terminal plates 67 and 68, respectively, that are held against the rear surface of the part 47 of the refractory member 19 by co-operating machine screws 69 and 71 extending therethrough and held by co-operating nuts 72. The two ends of the resistor member 21 may be electrically connected to the terminal plates 67 and 68 by means of the machine bolts 69 and 71.

37 The device embodying my invention thus provides a single member for pivotally supporting a reflector and a heating unit on a

base, for carrying the entire device and for clamping the rearwardly removable heating unit in its proper operative position in the reflector. It may, if desired, serve also as a 5 mounting means for a name plate 73 (see Fig. 2) that is suitably riveted thereto.

The single member constituting the carrying means, the pivotal supporting means and the heating unit clamping means may be 10 easily and quickly manufactured and may be assembled in its proper operative position on the heater and may be easily and quickly removed therefrom.

Various modifications and changes may be 15 made without departing from the spirit and scope of the invention, and I desire therefore that only such limitations shall be placed thereon as are imposed by the prior art.

20 I claim as my invention:

1. In an electric heater, the combination 25 with a concave reflector, and a base, of an extended arcuate member, having its lower end pivotally mounted on said base and having the reflector secured thereto intermediate its ends.

2. In an electric heater, the combination 30 with a reflector, and a base, of an extended member having the reflector secured thereto intermediate its ends, having its lower end pivotally mounted on said base, and comprising a handle portion at its upper end for carrying said heater.

3. In an electric heater, the combination 35 with a reflector, of a combined heater-carrying and heater-supporting member, of substantially arcuate form and directly secured to the rear surface of said reflector.

4. In an electric heater, the combination 40 with a reflector, of an elongated heater-carrying member directly secured to the rear surface of said reflector and comprising means for pivotally supporting the same.

5. In an electric heater, the combination 45 with a reflector, and a heating unit, of a reflector-supporting and heating-unit-clamping member.

6. In an electric heater, the combination 50 with a reflector, a heating unit, and a base, of a single means for pivotally supporting said reflector on said base and for clamping said heating unit in its proper operative position relatively to said reflector.

7. In an electric heater, the combination 55 with a reflector having an axial opening therethrough, and a heating unit extending into said reflector through said opening, of a single member for permitting of carrying said reflector and for securing said heating

unit in its proper operative position in said 60 opening.

8. In an electric heater, the combination 65 with a reflector, a heating unit, and a base, of a single member for pivotally supporting said reflector on said base, for securing said heating unit in its proper operative position relatively to said reflector and for carrying said heater.

9. In an electric heater, the combination 70 with a reflector having an axial opening therethrough, a heating unit extending into said reflector through said opening and rearwardly removable therefrom, and a base, of a single member secured to the rear surface of the reflector for pivotally supporting it 75 on the base, and for clamping the heating unit against the reflector.

10. In an electric heater, the combination 80 with a reflector having an axial opening therethrough, a heating unit extending into said reflector through said opening and rearwardly removable therefrom, and a base, of a single member secured to the rear surface of the reflector for pivotally supporting it on the base, for clamping the heating unit 85 against the reflector and for constituting a carrying means for said heater.

11. In an electric heater, the combination 90 with a reflector, a heating unit, and a base, of a single elongated member having means at its lower end for a pivotal mounting on the base, and having also means for securing said heating unit in its proper operative position in said reflector when secured to the rear surface thereof.

12. A reflector heater comprising, a base 100 having an upright portion, a dished heat reflector, and a bracket on the back of said reflector and dished less than said reflector to contact only the deepest portion of said reflector and one end thereof formed with a handle bent outward from said reflector to keep the handle cool and the other end thereof hinged to said upright portion.

13. A reflector heater comprising, a base 105 having an upright portion, a dished heat reflector, a dished bracket on the back of said reflector and one end thereof formed with a handle and the other end thereof formed with a pair of ears straddling said upright portion, a hinge pin through said ears and through said upright portion, and means on said hinge pin to adjust the friction between said ears and said upright portion.

In testimony whereof, I have hereunto 115 subscribed my name this 27th day of March 1924.

ORA A. COLBY.
